UNITED STATES PATENT OFFICE

MARCUS S. ROOSEVELT, OF DETROIT, MICHIGAN, ASSIGNOR TO THE HAMILTON AUTO-GRAPHIC REGISTER CO., OF HAMILTON, OHIO, A CORPORATION OF OHIO

CONTINUOUS STATIONERY APPARATUS

Application filed July 22, 1929. Serial No. 379,921.

My invention relates to improvements in apparatus to be used in filling in forms arranged in continuous sheets and objects of my improvements are to secure greater accuracy of alignment of the various sheets, to obviate the confining of air between the separate sheets and to avoid accidental displacement of the sheets from the apparatus.

In the accompanying drawings:

10 Figure 1 is a side view of an apparatus embodying my invention.

Figure 2 is an end view thereof. The strips of forms being removed and a part being broken away to more clearly show the construction.

15 Figure 3 is a sectional elevation, to an enlarged scale, of the upper right hand portion of the apparatus, as shown in Figure 1.

Figure 4 is a detail sectional elevation of 20 the clutch for preventing the accidental displacement of the strips of forms.

Figure 5 is a section of the upper left hand portion of the apparatus, as shown in Figure 1.

25 Figure 6 shows a section of the strip of forms.

Figure 7 is an elevation looking from the left of Figure 5.

Figure 8 is a sectional detail.

30 Figure 2 is a standard supporting a horizontal frame 3 at its upper end. 5 is a round bar extending transversely across the frame between the side pieces thereof. 6 is a table upon which the stationery is received to be 35 filled in by a typewriter adapted to the purpose and indicated at 28 in Figure 1. 7, 7, are stationary positioning pins extending upward from the table 6 a short distance near the delivery edge thereof. 26 is a

40 presser bar adapted to act upon the surface of the paper upon the table 6. There are holes in the bar 26 to permit the passage of the pins 7. 24 is a treadle adapted through a connection 25 to raise the presser bar 26 45 from the form strips and above the pins 7, 7.

8, 8 is a vertical frame having two side pieces, each of which has a vertical central slot 8a therein. 9, 9, 9, 9 and 10 are rollers adapted to rotate in the slots 8a and slide longitudinally therein. 11 indicates strips of forms, one strip passing under each of the rollers 9 and adapted to receive a transfer copy from the impression on the first sheet. 12 is a sheet of forms adapted to receive the original impress from the typewriter 28. 50 The sheets 11 and 12 are wound upon a roll 14 suspended in hangers 13 from the frame 3.

15 indicates stationary guide rollers arranged horizontally, transversely of the machine with their outer edges in a substantially vertical plane, in line with the outer edges of the rollers 9 and 10. 60

8ab is a horizontal slot extending from the upper end of the slot 8a to the outer edge of the side piece of the frame 8 and bridged by the piece 8ac on the outer surface of said side piece. The slot 8ab permits the entrance of a pintle of the roller 9 or 10 into the slot 8a. 65

16 is a guide roller extending horizontally across, between the side pieces of the frame 8 below the rollers 15 with its outer edge in the plane of the outer edges of said rollers. The form strips 11 pass from the roll 70 14 severally under the various rollers 9 to the roller 16 and then over the several rollers 15 to and over the guide bar 5 and then to and along the table 6 and have at their delivery ends the apertures 12a (Fig. 6) engaging over the pins 7, 7. The rollers 9 act by their weight to put the strips 11 under slight tension to hold the same in place. 75

15a is a roller extending transversely across the frame 3. Each of the ends of the roller 15a is mounted in an inwardly extending horizontal arm 20a of a bell-crank lever 20 pivoted at 21 to a side piece of the frame 3 and located so that its outer edge 85 is in the plane of the rollers 15 and above 90

the same. 20b is an outwardly extending arm of the bell-crank lever 20.

There is a slot 23 in the arm 20b. 22 is a rod adjustably clamped at its ends in the slots 23 of the arms 20b of the bell-crank levers 20.

The strip of forms intended and adapted to receive the original impression passes from the roller 14 beneath the roller 10 to the roller 16, over the roller 15a to the strips 11 passing over the bar 5 and has its apertures 12b engaging over the pins 7, 7. The weight of the roller 10 maintains the strip 12 in tension, which tension acts upon the roller 15a to hold the bell-crank lever 20 rocked to the limit of its travel, in a counter-clockwise direction.

17 is a rock shaft pivoted at its ends in the uprights of the frame 8 and extending parallel and adjacent to the outer edge of the roller 16. 18 is a clamping cam upon the rock shaft 17 adapted, when turned in a counter-clockwise direction to engage against the form strips passing over the roller 16 to prevent the retraction of said strips. 19 is a connecting rod joining an eccentric point of the rock shaft 17 to the bar 22. Thus when the strip 12 passing over the roller 15a is held in tension, the bell-crank lever 20 is rotated, turning the rock shaft 17 and drawing the clamping cam 18 away from engagement with the strips upon the roller 16. Should the delivery end of the strip 12 be released, the tension would no longer exist and gravity would carry the arm 20b downward, forcing the cam 18 against the strip 12 and roller 16 holding the strips 11 and 12 in position and not allowing them to fall from the machine under the influence of the rollers 9 and 10.

Of course the transfer sheets 11 are held in the same way as the sheet 12 and at the same time.

The arrangement of the rollers 15, 15a in a substantially vertical plane obviates the trapping of air between the form strips and the relative movement or creeping of said strips, so that the copies from the impress on the original sheet comes accurately in place on the transfer sheets.

All the form strips coming from the rollers 15 and 15a rise somewhat to engage over the bar 5 and approach each other gradually, so that the air between the strips is completely displaced.

The various strips where they come together simply lie against each other without pressure or friction one against the other, so that the tension on each sheet is between the engaging pins 7 and the weight roller.

Thus any one, or all, of the strips being loosened from the pins 7 may be drawn out, corrections made thereon and returned ac-

curately to place, unless the strip 12 is suddenly released, in which case the cam 18 would clamp against the form strips and prevent the backward movement thereof under the pull of the weight rollers. As each strip is free to move relative to the others it is accurately positioned by its engagement with the pins 7, 7. And each strip exerts its own tension against said pins and does not also carry a part or all the tension of the other strips, as has hitherto occurred in other forms of the apparatus.

If the form sheets are accidentally released they will not fall from the machine, as in previous devices, but will be held by the automatic action of the clamp 18.

The form strips are sometimes stored in successive folds instead of rolls, in which case a shelf would be substituted for the shaft of the roll and the strips would be delivered from this source in the same way.

What I claim is:

1. In an apparatus of the kind described, means for automatically preventing retraction of the strips and means dependent upon the integrity of a strip for preventing the operation of said automatic means.

2. In an apparatus of the kind described, a clamping means adapted to prevent the retraction of a strip, means for putting said strip under tension and means whereby said strip, when under tension, holds the first mentioned means out of engagement with said strip.

3. In an apparatus of the kind described, a clamping device adapted to permit the forward movement of a strip and to prevent the backward movement of the same, a roller located beyond said clamping means and connected to said clamping means to actuate the same, a strip passing over said roller, and means for putting a tension on said strip, whereby tension on said strip shall hold said clamping means disengaged.

4. In an apparatus of the kind described, a roller, a strip passing over said roller, a clamp adapted to engage said strip and press it against said roller to prevent the retraction of said strip, a lever pivoted beyond said roller connected to said clamp and biased by gravity to hold said clamp in engagement with the paper and roller, a second roller eccentrically pivoted on said lever, said strip passing over said second roller, means for holding said strip under tension, said second roller and strip being so arranged that the tension on said strip shall act through said second roller to turn said lever and draw said clamp out of engagement with said strip.

5. In an apparatus of the kind described, the combination of a plurality of strips adapted to be fed to the apparatus, a clamping device adapted to engage said strips and be disengaged therefrom, means for nor-

mally maintaining a tension on one of said strips, means connecting said strip with said clamping device so that a tension on said strip shall hold said clamping device out of engagement with said strips, said clamping device being adapted to engage said strips when not constrained by said tensioned strip, as and for the purpose described.

In testimony whereof, I sign this specification.

MARCUS S. ROOSEVELT.
